ATTORNEY

UNITED STATES PATENT OFFICE.

ISAAC B. KLEINERT, OF NEW YORK, N. Y.

WINTER CAP.

SPECIFICATION forming part of Letters Patent No. 239,804, dated April 5, 1881.

Application filed March 1, 1881. (Model)

To all whom it may concern:

Be it known that I, ISAAC B. KLEINERT, of New York city, in the county of New York and State of New York, have invented certain new and useful Improvements in Winter Caps; and I do hereby declare the following to be a full, clear, and exact description of the invention, such as will enable others skilled in the art to which it pertains to make and use it, reference being had to the accompanying drawings, which form part of this specification.

My invention relates to that class of winter caps which are provided with an adjustable band adapted to be drawn down over the neck and ears of the wearer when desired, and is particularly designed to provide a cap of the character designated which shall combine cheapness of production, durability and reliability in use, with comfort and protection, and an elegant and neat appearance.

With these ends in view my invention consists in certain details of construction and combinations of parts, as will be hereinafter described, and pointed out in the claims.

In the accompanying drawings, Figure 1 is a view of a cap fashioned in accordance with my invention, a portion of the sliding band of said cap being turned back to show the manner of its attachment to the crown thereof. Fig. 2 is a view of the cap as it appears with the sliding band drawn down to protect the ears and neck, and Fig. 3 is a view of the sliding band as it appears when detached from the cap.

While the drawings represent a cap of the style most commonly used, my improved sliding band may be applied to any style of cap that conforms to its general outline.

The cap shown is constructed of sector-shaped sections of cloth, the front sections, A and B, which form the front of the crown, being enough longer than the sections forming the rear portion thereof to extend down and cover the visor C. The rear crown-sections, D E F G, are cut from one to one and a half and two inches shorter than in the common construction of this variety of cap, and a muslin hat-band, A², is inserted, to form the lower edge of the cap proper. This style of cutting is found to be a valuable step in cap-making,

inasmuch as less material is required and a cheap band is inserted in lieu of the cloth, with the gain of increased stiffness, lightness, and neatness of form, as muslins are not as 55 cumbrous and heavy in folding as are the heavy woolen cap-stuffs.

The sliding band I may be cut from a single piece of cloth or be formed of two pieces of cloth joined midway of its length, or it may 60 be made of two long strips of cloth joined at the folding-point thereof.

The upper edge, l, of the said band I is stitched to the rear portion of the cap, at or near the point where the upper edge, m, of the muslin 65 is joined thereto. In stitching the band to the cap, as described, the band is laid flat on the body of the cap in such manner that its edge runs parallel with the upper edge of the muslin band aforesaid. The object of thus 70 disposing the sliding and muslin bands is to arrange them neatly and compactly, and avoid the heavy and bungling appearance of folded cloth, and also to save skilled labor in the finishing-off stage of cap-making, for the application 75 and attachment of an extension-band to the body of a cap is a very important step, and can only be satisfactorily effected by skilled labor. After the sliding band has been secured to the cap, as described, it is folded upon itself to form 80 a fold above the upper edge of the muslin band, and in such manner that its lower edge will fall just below the lower edge of the muslin band and completely obscure it. The ends 85 A A' of the band I are quite narrow, and are brought around in front of the cap and secured in the central portion of the visor, or, if the cap be a visorless one, at a point midway of its front crown-section.

If desired to still further economize material, the muslin band may be extended to encircle the cap, and the cut of the ends of the sliding band be conformed to it. In most of the caps of this character the ends of the sliding band are tied or buttoned in front, and must be undone when the band is to be used as a protector; but with my cap this is not necessary, and, moreover, there is an object in securing the ends permanently to the visor, as by so doing, when the band is drawn down with the exception of its ends secured to the front portion of the cap, the lower rear portion of the

band will be drawn inward, and thus more effectually protect the neck from the wind and cold.

The objections urged against adjustable protecting-caps include those of a bungling and uncouth appearance, owing to an unskillful disposition of material, of which there must be, in order to fulfill the design of the cap, much more than in caps of the ordinary and simple make, and of the difficulty of their construction, as the application of a sliding band to a partially-completed hat or cap requires no small amount of dexterity.

The application of the sliding band to my improved style of hat or cap is simple, and can be done without danger of being put on askew, and inasmuch as it is accomplished with a decided saving of skilled labor, the cost of production of the cap is greatly reduced.

It is apparent that I may modify the form of caps shown in many ways without departing from the spirit of my invention, and hence I would have it understood that I hold myself at liberty to make such changes and alterations as fairly fall within the spirit of my invention.

Having fully described my invention, what I claim as new, and desire to secure by Letters Patent, is—

1. In a cap, the combination, with the crown thereof, of a sliding band having its upper edge secured above the lower edge of the rear portion of the crown, said band being folded upon itself to form a fold above the point to which it is secured, and in such manner that

its lower edge will be even with the lower edge of the crown, substantially as set forth.

2. A cap having a muslin or equivalent band extending around the rear portion of the crown, or entirely encircling the crown, and a sliding band adapted to be drawn down over the neck, and having its upper edge secured at or near the upper edge of said band, and its free ends secured to the front crown-section of the cap, said band being folded upon itself to form a fold above the upper edge of the muslin band, and returning in such manner that its lower edge will be even with and obscure the said muslin band, substantially as set forth.

3. In a cap the crown of which is cut shorter than its designated height, and which is completed by a band of inexpensive material attached to its lower edge, a folded sliding band attached to the cap-crown to hide the inexpensive band attached thereto, substantially as set forth.

4. A cap the crown of which is cut shorter than its designed height, and which is completed by a band of inexpensive material attached to the lower edge of the cap-crown proper while the same is being sewed together, substantially as set forth.

In testimony that I claim the foregoing I have hereunto set my hand and seal this 16th day of February, 1881.

ISAAC B. KLEINERT. [L. S.]
